UNITED STATES PATENT OFFICE.

JOSEPHINE LACY, OF FREEPORT, PENNSYLVANIA.

WINDOW-CURTAIN POLE.

SPECIFICATION forming part of Letters Patent No. 643,142, dated February 13, 1900.

Application filed August 8, 1899. Serial No. 726,528. (No model.)

To all whom it may concern:

Be it known that I, JOSEPHINE LACY, a citizen of the United States of America, residing at Freeport, in the county of Armstrong and State of Pennsylvania, have invented certain new and useful Improvements in Window-Curtain Poles, of which the following is a specification, reference being had therein to the accompanying drawings.

10 This invention relates to certain new and useful improvements in curtain-poles, and has for its object to provide novel means whereby the use of rings and pins is entirely dispensed with. Furthermore, the invention 15 aims to construct a curtain-pole of this class that may be easily and conveniently draped and the curtain readily released from the pole when desired.

The invention has for its further object to 20 provide novel means that will admit either one or both curtains to be removed or draped, as the case may be.

A still further object of the invention is to 25 design a curtain-pole of this class that will be extremely simple in its construction, strong, durable, and comparatively inexpensive to manufacture; furthermore, one that may be easily attached to other curtain-poles now in use or may be attached independently, as desired.

With the above and other objects in view the invention finally consists in the novel construction, combination, and arrangement of parts to be hereinafter more fully described, 35 and specifically pointed out in the claims.

In describing the invention in detail reference is had to the accompanying drawings, forming a part of this specification, wherein like numerals of reference indicate corresponding parts throughout the several views, 40 and in which—

Figure 1 is a front view of the top of a window-frame provided with one of my improved curtain-poles. Fig. 2 is a top plan view of the same. Fig. 3 is a perspective view of the same. Fig. 4 is an enlarged side view of the same. Fig. 5 is a side view of the same, showing a modified form of the attachment in use. Fig. 6 is a perspective view of the pole proper, 50 partly broken away.

Referring to the drawings by reference-numerals, 1 indicates the window-frame, and 2

the curtain-pole proper, said curtain-pole being fluted or corrugated, as shown at 3.

The reference-numeral 4 indicates a pair 55 of supporting-brackets which are secured at one end to the window-frame 1 and are adapted to support the curtain-pole. These brackets are provided on their outer end with the head 5 and carry a bearing-strip 6, the rear face of 60 which is placed against and adjacent to the front face of the window-frame. The ends of the said rods 4 may be pointed, as at 7, (see Fig. 4,) or they may be screw-threaded, 65 as desired.

Upon the curtain-pole 2 centrally is rigidly secured a plate 8, to which are pivotally attached at 9 9 rods 10 10, said plate having formed centrally therein an aperture 11 for the reception of the rosette 12, the latter carrying a suitable ornament which will give a finished appearance to the curtain-pole and hide from view the ends of the rods 10 10. The said rods 10 10 are held in position and are adapted to engage hooks 13 13, arranged near 70 the end of the curtain-pole, said rods 10 10 being also adapted to rest in one of the flutes 3, thereby obtaining means to more clearly clamp the curtain and retain the same in the proper position. 75

The reference-numeral 14 represents a rear rod arranged on the opposite side of the pole from the rods 10 10 and extending in alignment with the curtain-pole almost the entire length, said rod 14 being pivotally secured at 85 15 and its other end being retained by a hook 16, which is similarly arranged to the rear face of the pole as the hook 13. The front face of the curtain-pole, near the ends thereof, is provided with spring-hooks 17, the latter being 90 adapted to engage an ordinary curtain-pole 18. (See Fig. 5 of the drawings.)

The rear rod 14 will serve to effectually retain and clamp the portion of the curtain that is draped over the pole and the rods 10 will 95 serve to retain that portion of the curtain that is draped over the front of the pole.

From the above description the numerous advantages afforded by the use of my improved curtain-pole will be readily apparent 100 and a further description of the same is thought unnecessary. However, it will be particularly noted that various changes may be made in the details of construction without

departing from the general spirit of my invention.

Having thus fully described my invention, what I claim as new, and desire to secure by 5 Letters Patent, is—

1. In a curtain-holding device the combination of a fluted or corrugated curtain-pole, a central plate having pivotally secured thereto rods, hooks arranged on said pole adapted 10 to retain said rods, a rear rod pivotally secured at its one end, and a hook arranged to the rear face of the pole adapted to retain said rod, substantially as described.

2. In a curtain-holding device, the combination of a curtain-pole, rods pivotally secured thereto, hooks secured to the said pole and adapted to retain the said rods, a rear rod pivotally secured at one end to the said pole, a hook secured to the said pole and adapted to 20 retain the said rod, and a spring-hook mount-

ed upon each end of the said pole, substantially as set forth.

3. In a curtain-holding device, the combination of a pair of supporting-brackets, a curtain-pole adapted to be supported thereby, a 25 central plate secured to the said pole, a pair of rods pivotally secured to the said plate, hooks secured to the said pole adapted to retain the said rods, a rear rod pivotally secured at one end to the said pole, a hook secured to the pole for retaining the said rod, and a spring-hook mounted upon each end of the said pole, substantially as described. 30

In testimony whereof I affix my signature in the presence of two witnesses.

JOSEPHINE LACY.
